ATTORNEYS.

UNITED STATES PATENT OFFICE.

FRANK A. EARHART, OF PHILADELPHIA, PENNSYLVANIA.

APPARATUS FOR FORMING AND SHAPING HAT BRIMS.

Application filed June 8, 1922. Serial No. 566,677.

To all whom it may concern:

Be it known that I, FRANK A. EARHART, a citizen of the United States, residing in the city and county of Philadelphia, State 5 of Pennsylvania, have invented a new and useful Apparatus for Forming and Shaping Hat Brims, of which the following is a specification.

My invention relates to a novel method 10 of and apparatus for forming or shaping hat brims without marring or injuring the material thereof, provision being made for effectively and quickly forming hat brims by my novel method and apparatus, whereby 15 a superior product is more cheaply and effectively produced than heretofore, the novel features of my invention being fully set forth and pointed out in the claims.

For the purpose of illustrating my invention, I have shown in the accompanying drawings a form thereof which is at present preferred by me, since it will give in practice satisfactory and reliable results, although it is to be understood that the various instrumentalities of which my invention consists can be variously arranged and organized and that my invention is not limited to the precise arrangement and organization 25 of these instrumentalities as herein shown 30 and described.

Figure 1 represents a top plan view of an apparatus for carrying out my invention.

Figure 2 represents a section on line 2—2 of Figure 1,

Figure 3 represents a section on line 3—3 of Figure 1.

Figure 4 represents a perspective view of a plurality of plates and spurs employed in carrying out my novel method, the same 40 being shown in detached position.

Figure 5 represents a side elevation of a finished hat brim produced by my novel method, and

Figure 6 represents a sectional view showing the manner of assembling the elements of sheets of which the hat brim is composed.

Similar numerals of reference indicate corresponding parts.

Referring to the drawings,

In carrying out my invention, I have shown in Figure 6, as section of the finished hat brim as indicated at 1, which is composed of the lower sheet or piece 2, as of 50 velvet or the like, the upper sheet 3 also of velvet or the like and the intermediate

stiffener 4 of buckram or the like, the nap of the velvet sheets being outside.

In carrying out my invention, the lower sheet 2 of velvet is first coated on its top or side opposite to the nap with a suitable cement or adhesive material and is then placed upon the block or die 5.

A cord or other fastening means 19 is then tied around the outer periphery of said sheet 2 above the pins 19^x, it being apparent 65 that said die or block 5 has its upper surface shaped to the desired conformation as seen in Figures 2 and 3.

The lower plate 6, best seen in Figure 4, is then placed in position upon the lower 70 velvet sheet 2 and pressed downwardly so that the spur 7 is forced through the sheet 2 and passed through the hole 8 in the die.

The treadle 27 is then depressed by the operator so as to press the plunger 18 downwardly upon the plate 6, after which the wedge 13 is inserted through the slot 14 of the spur 7, so that the upper edge 15 of said wedge contacts with the walls 16 as will be understood from Figure 3, so that the plate 6 is held firmly in its downward position against the top of the lower sheet 2 and the treadle is released.

The intermediate sheet of buckram 4 or the like having been coated with cement or other suitable adhesive material on both sides is then placed on the top of the lower velvet sheet 2, covering also the top of the plate 6, after which the upper plate 9 is placed in position and its spur 10 is passed 85 through the top sheet 4 of buckram and the bottom sheet 2 of velvet, said spur also passing through the hole 11 in the plate 6 (see Figure 4).

The treadle 27 is then depressed to bring 95 the plunger 18 down upon the upper plate 9 and the sheets below the same, after which a second wedge 13 is inserted through the slot 13^x in the spur 10, so that both the plates 6 and 9 are rigidly locked in position 100 and the sheets of buckram and the bottom velvet sheet are compressed, as seen in Figure 2.

The bottom side of the upper sheet 3 of velvet is next coated with cement or other 105 adhesive material and is placed upon the top of the sheet of buckram and the top of the plate 9, the plunger 18 is then brought into the position seen in Figures 2 and 3 by the treadle 27.

The top surface of the top sheet of velvet 3 is manipulated or manually smoothed around its outer surface to conform to the top of the die or block 5, after which its outer periphery is secured by a cord passing around the top of the pins 19^x.

It will be understood that the die 5 is heated by any suitable means (not shown) so that while the plates 9 and 6 and the sheets 3, 4 and 2 are in the position seen in Figure 2 and 3, the cement or adhesive material common to their contiguous surfaces will be melted and will firmly adhere to the contiguous surfaces composing the hat brim, which is designated as 33.

The hat brim 33, having been shaped or formed, the cords 19 are then removed from the pins 19^x, the wedges 13 are removed and the plunger 18 elevated, after which the finished shaped hat brim 33, together with the plates 6 and 9 are removed, and the center portion of the brim can be cut out at 34 by any suitable means and the crown 35 secured in place, as is customary.

The plunger 18 can be actuated by any suitable means and I have shown the same as secured to the arms 20, bolted to the transverse cross piece 21 through whose outer ends pass the rods 22, through whose lower ends pass the transverse rod 23.

24 designates a transverse, stationary rod secured in the bottom of the framework or uprights 25. The side arms 26 are supported at their rear ends by the transverse stationary rod 24, which passes through them, and through the front ends of said arms passes the transverse rod 23. The front treadle 27 has its rear portion mounted on the transverse stationary rod 24 and projects forwardly over the rod 23, so that when the treadle is depressed, the rod 23, arms 26 and side rods 22 and their adjuncts descend, carrying with them the plunger 18.

The upward movement of the treadle is assured by the tension of the springs 28, whose lower ends are attached to the rod 23 and their upper ends to the cross rod 29.

The rods 22 are guided in the holes 30 of the plate 31, which carries the posts 32, which support the die block 5.

It will of course be evident that the plunger 18 can be actuated by other means than that shown.

The die 5 is preferably provided with a central seat 17, which receives the central portion of the brim blank, and the plates 6 and 9.

It will be apparent from the foregoing that by my novel method of making hat brims, the material composing the hat brim surface proper is not impaired or injured by pressure thereon, since the pressure is applied to the central portion of the brim, which is afterwards cut out and to the exterior peripheral edge of the brim while

the latter is engaged by the cord 19, so that the material composing the brim is not injured in any way during the operation of its formation.

It will be understood that while I have described the brim in the present instance as being composed of upper and lower sheets of velvet with the nap outside and the intermediate stiffener or sheet of buckram, the brim may be composed of other materials than those described, as is evident.

It will further be apparent that hat brims constructed in accordance with my invention can be expeditiously and effectively produced with a minimum expenditure of time and labor, and that my invention is applicable to existing machines equipped with treadle mechanism and plunger of the character described.

It will be apparent that while I have described my invention as particularly adapted for the making of hat brims the same may be employed for making the hat proper or any portion of the hat and it may also be employed for making other devices wherein it is desired to secure together and shape a plurality of sheets of material.

It will now be apparent that I have devised a novel and useful method of and apparatus for forming and shaping hat brims which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:

1. In an apparatus of the character stated, a heated die having pins secured to its outer periphery, holes through said die and a plurality of plates having spurs depending therefrom and passing through the holes in said die, wedges passing through slots in said spurs, a plunger above said plates, and means including a foot treadle for actuating said plunger.

2. The herein described device for applying pressure to the central portion of hat brims, comprising a heated die having a hole therethrough, a plate having a spur depending therefrom and provided with a slot, and a wedge passing through said slot and contacting at its upper edge with projections from said die.

3. In a device of the character stated, a heated die having means on its outer periphery for securing a hat brim thereto, a lower plate having a hole therein and a spur

depending therefrom, and provided with a slot, said spur passing through a hole in said die, the upper plate having a spur depending therefrom and passing through the hole in said lower plate and provided with a slot, a pair of wedging members passing through said slots for drawing said plates towards said die, a plunger located

above said plates, and spring pressed means including a foot treadle for actuating said plunger. 10
